CLAIM

The ornamental design for a curling iron heater, as shown and described.

DESCRIPTION

FIG. 1 is a top perspective view of a curling iron heater showing my new design;

FIG. 2 is a front elevational view thereof;

FIG. 3 is a right side elevational view thereof, the side opposite being a substantial mirror image of the side shown;

FIG. 4 is a rear elevational view thereof;

FIG. 5 is a top plan view thereof; and,

FIG. 6 is a bottom plan view thereof.
